CLAIM

The ornamental design for a “set top box”, as shown and described.

DESCRIPTION

FIG. 1 is a right, top and front perspective view of a set top box showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is a left, bottom and rear perspective view thereof. The broken lines shown represent unclaimed subject matter and form no part of the claimed design.
